COMPUTING MACHINE

Lawrence E. Lentz, New York, N. Y., assignor to
 Underwood Elliott Fisher Company, New York,
 N. Y., a corporation of Delaware

Application March 16, 1934, Serial No. 715,820

15 Claims. (Cl. 235—60)

This invention relates to improved zero or space-key mechanism for adding machines of the class exemplified in Sundstrand Patent No. 1,583,102, issued May 4, 1926, in which ten digit-keys are operable to set indexing mechanism preparatory to printing and adding the indexed amount.

A feature of the invention resides in providing novel means whereby operation of any one of a plurality of multiple-zero keys effects automatic cycling of the machine in sequence to the setting of the zero-stops and the jumping of the carriage. Therefore, the operator need not do anything further after depressing the multiple-zero key. Thus, for indexing and computing or printing an amount terminating in a succession of zeros, all the operator needs to do is to touch the index-keys for the amount-digits preceding said zeros, and then to touch the appropriate multiple-zero key, upon the down stroke of which, the required number of zeros will be indexed; and upon the up stroke, the carriage will jump the required number of spaces, and the machine-motor will finally be connected to automatically cycle the machine to cause the printing and adding of the number.

There may also be provided a single-zero key connected to cycle the machine in order that when an amount terminates in a single zero, the indexing of said single final zero will also cycle the machine, to thereby dispense with an otherwise necessary operation of the usual cycling key. In this way, the ordinary zero-key, included in the complement of digit-keys, may be operated for indexing a zero at any place between significant digits of an amount, and any of the motor-tripping zero-keys may be operated at the conclusion of indexing an amount terminating in one or more zeros.

Other features and advantages will hereinafter appear.

In the accompanying drawings,

Figure 1 is a perspective view showing the improved zero-key mechanism and related parts of the Sundstrand machine.

Figure 2 is a fragmentary plan view showing the step-by-step feeding carriage released from its escapement and arrested by one of the supplemental stops as a result of operation of a multiple-zero key.

Figure 3 is a detail view of a rack and restorer for the supplemental carriage-stops.

Figure 4 is a top plan view of the improved zero-key mechanism and related parts of the Sundstrand machine.

Figure 5 is a side view diagram of the Sundstrand cycling mechanism.

Figure 6 is a fragmentary perspective view illustrating the partial restoration of the cycle-tripping means to prevent repetition of the cycle which follows operation of one of the new zero-keys.

Figure 7 is a side elevation view of the improved zero-key mechanism and related parts, some of which are shown in section for clearness.

Figure 8 is a plan view diagram showing how the release of the step-by-step feeding carriage, following operation of one of the new zero-keys, causes operation of means for starting a cycle of the machine.

Figure 9 is a plan view diagram illustrating restoration of the zero-key-operated cycle-tripping parts by the return of the carriage at the end of the machine-cycle, and also illustrating the manner of restoring the supplemental carriage-stops.

Figure 10 is a fragmentary plan view illustrating the restoration to normal positions of an escapement-rack for the carriage and a zero-key-operated rack-releasing member just prior to the end of a cycle.

The invention is shown applied to a Sundstrand adding machine in which the usual amount-indexing mechanism includes a single set of ten digit-keys 15, (Figs. 4 and 7), mounted on key-stems 16. Depression of any digit-key 15 causes its stem 16 to rock a bell-crank 17 connected by a link 18 and a bell-crank 19 to the forward end of a stop-setting rod 20 slidably guided at its rearward end in a post 22. The bell-cranks 19 are associated with the several digit-keys 15 and are pivoted on a common vertical fulcrum-rod 23 and the stop-setting rods 20 are arranged in a single vertical column.

The rearward thrust of any stop-setting rod 20 effected by depression of the corresponding digit-key 15 in indexing an amount sets a corresponding digit-stop 24 in one of several vertical columns of a nest or field of said stops 24, the indexing starting with the first column of stops from the left and progressing column by column toward the right at successive operations of the digit-keys 15. For the latter purpose, the post 22, which guides the rear ends of the stop-setting rods 20, is part of a traveling frame 25 swingable about a pivot 26, so that the rear ends of the single column of stop-setting rods 20 may traverse the several columns of stops 24. Such traverse is effected step by step by means of an escapement-rack 27 pivoted at a fixed point 28 of the machine-framework and engaging a corner 55

- of the post 22, which thus acts as a holding dog, one or another of the teeth of said rack 27 being normally caught over said corner and the rack being yieldably held against the post 22 by a spring 29. The traveling frame 25 which carries the post 22 is constantly urged in clockwise direction of Figure 1, by a spring 30, and is restrained, as will be evident from Figure 1, by the escapement-rack 27.
- 10 For operation of the escapement-devices at operation of any digit-key 15, the corresponding bell-crank 19 operates a universal bar 32 swingable by means of end arms 33 about the axis of fulcrum-rod 23 of the bell-cranks 19. The upper arm 33 is part of a bell-crank to which is connected a thrust-rod 35, also guided at its rear end in the post 22, to engage whatever tooth-edge 36 of the escapement-rack is caught over the corner of the post 22. Thus, a rearward thrust of the escapement-actuating rod 35, attending operation of any digit-key 15 to set a stop 24, causes the escapement-rack 27 to be displaced from the dog or post 22 at the down stroke of the key, whereupon the traveling frame 25, under the pull of spring 30, swings slightly clockwise until the rear end of the rearwardly-thrust rod 35 forming another dog is caught by the released tooth of the escapement-rack. This slight swing of the frame 25 is sufficient to bring the corner of the post 22 past the released rack-tooth, but does not displace the column of stop-setting rods 20 enough to prevent the operated rod from setting the digit-stop 24 in the column corresponding to the escaped tooth of the rack 27.
- 30 On the up stroke of the operated key 15, the corresponding stop-setting rod 20 is withdrawn and the rod or dog 35 is also withdrawn within the post 22, so that the frame 25 resumes its swinging motion to the right until the post 22 is caught by the next tooth of the escapement-rack, thereby aligning the column of stop-setting rods 20 with the next column of stops 24. Thus, at succeeding operations of the digit-keys 15 to index an amount, the digits of said amount are caused to be set up by having corresponding stops 24 projected rearwardly in consecutive columns, beginning with the first column at the left, of the nest or field of stops 24. The stops 24 are guided for endwise movement in a stationary frame 31.
- 50 The rearwardly-set digit-stops 24 act as stops for a set of reciprocatory denominational bars 38, each bar having a rack 39 to actuate a corresponding computing pinion 40, and also having a set of digit-types 41 operable by the usual Sundstrand type-striker 42 to print against a platen 43. The denominational bars 38 are guided for up-and-down movement effected by the usual cycling mechanism, which includes individual partly-shown arms 44 operative to raise and lower the bars during a machine-cycle which follows the indexing of an amount by means of the digit-keys 15. In the Sundstrand machine, there is no digit-stop 24 for the digit "9", and therefore, the "9" digit-key 15 works only to actuate the universal bar 32 to advance the carriage a necessary step. A denominational-bar 38 indexed for "9" rises, during the cycle, to the limit of its movement to print or accumulate "9".
- 70 The indexing of an amount begins always at the first column from the left of the nest or field of digit-stops 24. Before the first key is struck, the whole nest or field of digit-stops 24 is in such position relatively to the denominational-bars 38 that, as indicated in Figure 4, said first column

of stops 24 is about one denomination space to the right of the co-operating part 48 of the bar 38 of lowest denomination.

In the Sundstrand machine, the above-described escapement-controlled movements of the frame 25 are employed to effect the relative shifts between the nest or field of digit-stops 24 and the denominational-bars 38, and to this end, the Sundstrand machine employs means including a carriage slide 46 coupled to the frame 25 by a pin-and-slot connection, as at 47, Figures 1, 7 and 9, said carriage slide 46 being guided on a cross-rod 45 for endwise movement. Said carriage slide 46 carries a post 52 whose upper end runs in a trackway formed in a stationary plate 15 53, Figure 7, whereby said carriage slide 46 is guided and kept from turning about said cross-rod 45. The transversely-guided carriage slide 46 serves to shift the usual transversely shiftable vertical extension rods 48 of the denominational-bars 38. Said vertical extension rods 48 form the aforementioned denominational-bar parts co-operating with the digit-stops 24. In order to be capable of such field stop-traversing movement, each rod 48 is connected to its denominational-bar 38 by an arm 49 hinged to the denominational-bar, as in Figure 7. The vertical extension rods 48 are slidably guided in the carriage-slide 46 for up-and-down movements, corresponding to the up-and-down movements of the 30 denominational-bars 38, and each extension rod 48 is connected to its arm 49 at 51 by the usual sliding connection, whereby the arm 49 may swing arcuately, while the extension rod moves transversely in a straight line. At each operation of a digit key 15, the carriage slide 46 and its extension rods 48 are positioned one denominational step to the right relatively to the groups of columns of digit stops 24, so that the indexed amount may be co-ordinated with the denominational rack bars 38 in accordance with the number of places in the indexed amount.

As shown in said Sundstrand Patent No. 1,583,102, a rock-shaft 56 is operable to drive co-operating mechanism (not shown herein) to 45 cycle the machine. For power operation of said shaft 56, a power-drive, such as shown in Sundstrand Patent No. 1,925,735, issued September 5, 1933, may be employed, and is tripable by a cycling key 57, Figures 4 and 5.

When the cycling key 57 is depressed, it rocks a crank-rod 58 operative through linkage, including parts 59, 60 and 61, to withdraw a pin 63 to release a spring-pressed clutch-dog 64. The clutch-dog 64 is mounted on a member 65 fastened to a crank-shaft 66 normally disconnected from a toothed driver 67 geared, as indicated in Figure 5, to an electric motor 68. The clutch-dog 64, when released, engages the toothed driver 67, and at the same time releases a switch-lever 60 70 to permit electric-circuit contacts 71 to close for starting the normally silent motor 68. The crank-shaft 66 thereupon makes one revolution, at the end of which the clutch-dog 64 is intercepted by the returned pin 63, and is thereby 65 caused to be withdrawn from the driver 67 in well-known manner. The clutch-dog is also operative at the end of said revolution to cam the switch-lever 70 to reopen the switch-contacts 71 to silence the motor. By the one revolution of the crank-shaft 66, the cycling rock-shaft 56 is rocked forward and then back through connections including an arm 72 fastened to said rock-shaft 56 and a link 73 which connects a crank 74 75

of the crank-shaft to a plate-like extension 15 of the rock-shaft arm 72.

The traveling indexing frame 25 rocks about its pivot 97 in clockwise direction (Fig. 4) as the 5 numeral keys, upon operation, to successively trip the escapement lever 21, to position the vertical column of stop pins 20 opposite successive vertical columns of stops 24, from left to right.

10 The leftwardly projecting arm of the indexing frame has a pin and slot connection 80 with the forward end of a frame-restoring slide 79 suitably connected for sliding movement to one wall of a stationary upright plate 162. This restoring 15 slide 79 is drawn rearwardly incident to the step-by-step rotation of the indexing frame 25 in clockwise direction.

15 A roll 78 on the forward end of the frame restoring slide 79 is adapted to be acted upon by 20 a restoring push-rod 77, the forward end of which normally lies in its advanced position.

25 This restoring push-rod is actuated from the crank shaft 56, as explained in patent to Sundstrand, 1,198,487, issued September 19, 1916, and 30 upon the forward rocking of the crank shaft 56, the push-rod is drawn rearwardly throughout its full travel which exceeds, in extent, the possible rearward travel of the roller stud 78 on the restoring slide 79, so that the forward end of the 35 push-rod 77 lies in rear of the stud. The rock-shaft 56, on its return stroke, advances the push-rod 77 to its normal position, and the push-rod, on such return, contacts the stud 78 to advance the restoring slide 79 to its home position. Thus, 40 said frame 25 and the thereto coupled shift-carriage slide 46 for the laterally shiftable denomination-bar-extension rods 48 will be restored to their normal or Figure 4 positions during the last part of the machine-cycle; and 45 incidentally the post 52 of said carriage slide 46 will cam to restored positions all the digit-stops 24 that were set prior to the cycle.

50 The stem 82 of a repeat-key 81 carries a stud 83 which, by setting said key to depressed position, prevents the forward portion of the push-rod 77 from rising, thereby rendering said push-rod inoperative to restore the carriage 25, 46 and the parts controlled thereby during the cycle.

55 The usual operation of said push-rod 77 and the disabling thereof by the repeat-key 81 are fully set forth in Sundstrand Reissue Patent No. 14,237, of December 26, 1916.

60 Referring now to the novel multiple-zero-key mechanism, a file of multiple-zero keys 84 is provided, and is preferably disposed between the cycling key 57 and the group of digit-keys 15, as in Figure 4. For illustration, six of said zero-keys 84 are shown. Each zero-key 84 is mounted on a stem 85 guided for endwise depression in 65 slots 86 of an upper plate 87 of the keyboard and in similar slots of an angle-bar 88 mounted below said keyboard-plate 87, as indicated in Figures 1, 4 and 7. For limiting its up-and-down movement, each zero-key stem 85 has stop-lugs 89. 70 As indicated in Figures 4 and 7, the foremost zero-key 84 of the file is for a single "0". The next key 84 is for "00", and so on, the rearmost key 84 being for six zeros, or "000000".

75 In order that depression of any zero-key 84 may set such number of zero-stops as corresponds to the number of zeros which the key represents, the following mechanism may be provided. For each zero-key, there is pivoted to the vertical flange of the key-guiding angle-bar 88 a corresponding bell-crank lever 90, Figures 1 and 7,

operable by depression of the zero-key whose lower end abuts an arm 91 of the bell-crank lever. A spring 92 co-operates with the bell-crank lever 90 to yieldably maintain the zero-key in its normal position. By means of said 5 bell-crank lever 90, acting through a link 93 and a lever 94, depression of the zero-key moves rearwardly a corresponding thrust bar 95 for setting an appropriate number of zero-stops, which stops will hereinafter be designated as 24°. 10

There is a similar linkage terminating at one end in a zero-stop-setting thrust bar 95 for every zero-key 84, and the several bars 95 may be banked, one above the other, as indicated in Figures 1 and 7. The forward end of each thrust 15 bar 95 is pivoted to a corresponding arm of its lever 94, as at 97. The several levers 94 are also banked one above the other, and are pivoted upon a common fulcrum-stud 98, Figure 1, for individual movement. Said stud 98 may be mounted 20 upon a plate 99 of the machine-frame, said plate also carrying the pivot 26 for the step-by-step feeding frame 25, and also carrying the fulcrum-rod 23 for the several digit-indexing bell-cranks 25. Each zero-stop-setting bar 95 has at its 25 rear end, a transverse edge 95a corresponding in length to the number of zero-stops 24° which the bar 95 is required to set simultaneously upon operation of its zero-key. Figure 1 clearly indicates the different lengths of the edges 95a of 30 the several zero-stop-setting bars 95, the bar with the longest edge, that is, the one for the "000000" key being the uppermost one of the bank of bars 95, the bar for the "0" key having the shortest edge 95a and being the lowermost one. 35

It is required that the zero-stop-setting edges 95a move collectively with the step-by-step feeding movements of the frame 25, since, in any digit-indexing position of said frame 25, all the edges 95a must begin at and include the zero-stop 24° in that column of the nest or field of stops 24 to which the column of stop-setting thrust-rod 20 points. For this purpose, said frame may have fastened thereto at 101, Figure 7, a vertical plate 102 which mounts the post 22 40 of said frame, as seen in Figure 1, and which also affords a laterally-extending ear 103 carrying a downwardly-projecting headed stud 104 which, for guiding and supporting the rear ends 45 of the thrust bars 95, passes through a slot 105 in each bar. Spacers 106, Figure 7, serve to slightly separate the rear ends of the thrust bars 95, one from the other. It will be seen now that in the step-by-step movements of the carriage 25, the thrust bars 95 swing about their pivots 50 55 97 on the levers 94, and that the latter are operative in any position of the group of thrust bars 95 to actuate said thrust bars 95 individually under control of the zero-keys 84. 60

In order that a zero-stop 24° may be set rearwardly by any one of the zero-key-operated thrust bars 95, each stop is formed, as indicated in Figures 1 and 7, to present an up-and-down extending face 107. A tongue 108 may extend 65 rearwardly from the lower face-forming part of the stop 24°, and serves to keep said face-forming part from being cocked sidewise by the thrust of the bar 95, said tongue being guided in a corresponding slot in a plate 109 which is part of the frame 31. A strip 110 co-operates with suitable slots in the plate 109 and in the rear wall of the frame 31 to slidably guide the zero-stops 24° for endwise movement, said strip being removably attached to said plate 109 to facilitate 70 the assembly of the zero-stops 24° in said frame 75.

31. Like the usual digit-stops, each zero-stop 24° has a detent-spring 111 to detain the stop in its normal, and its rearwardly-set positions determined by shoulders 112 on the stop, as indicated in Figure 7. In order that the frame or carriage 25, 46 may be caused to advance to an extent proportionate to the number of zero-stops 24° set by operation of one of the multiple-zero keys 84, to thereby bring the denomination-extension rods 48, into proper denominational co-ordination with the field of stops as indexed, the following mechanism is provided. Each zero-stop-setting thrust bar 95 has at its rear end a downwardly-extending tongue 113, the tongues of the several thrust bars 95 being transversely spaced similarly to the spacing of a transverse row of stops 114, one for each column of digit-stops 24. Depending on the position of the frame 25, and on which one of the zero-key-operated thrust bars 95 is actuated, the actuated thrust bar 95, by means of its tongue 113, will set the proper stop 114 for arresting the carriage 25, 46 when the latter is released from the control of the escapement-rack 27 by operation of a zero-key, as will presently be described. Each carriage-stop 114 may have a shoulder 115 engageable by the lower end of any tongue 113 for projecting said stop 114 rearwardly. A rearwardly-projected carriage-stop 114 may arrest the carriage-structure, which, it will be understood, includes the carriage slide 46, by intercepting a lug 116 of said carriage slide 46. These carriage stops 114 may be conveniently supported for back and forth sliding movement, 35 in parallel grooves or seats 130 (Fig. 3) formed transversely of a plate 129, secured by fastenings 128 (Figs. 1, 4, 8 and 9) to the under face of a control bar 127, extending transversely across the machine just beneath the line of depending stop-setting tongues 113 of the zero-stop setting thrust bars 95.

The shoulders 115 at the rear ends of the carriage stops 114 project upwardly above the plane of the control bar 127 to lie in the paths of the tongues 113 on the thrust bars.

The front ends of the carriage stops 114 extend forwardly of the forward edge of their supporting plate 129 and carry depending lugs 152 beveled at their lower ends to co-act with spring 50 detents 153 which operate to detain the carriage stops 114 in their effective or ineffective positions.

For releasing the carriage-structure from the escapement-rack 27, after the zero-stops 24° and a carriage-stop 114 have been set by operation of a zero-key, the following mechanism may be provided. Each zero-stop-setting thrust bar may have a laterally-extending ear 117, whereby, when the thrust bar 95 is projected rearwardly, said bar may rock an escapement-disabling lever 118, Figures 1 and 7. This escapement disabling lever 118 is pivoted to the frame-plate 102 at 119, and is articulated at its upper end to the front end of an escapement-disabling finger 120, whose rear end is slidably guided in a slot 121 of the post 22 and normally overlies the escapement rack 27 or a flange 124 formed thereon.

A spring 123 yieldably maintains the escapement-disabling lever 118 and its escapement-disabling finger 120 in normal position. The rear end of the finger 120 normally extends far enough beyond the flange 124, so that, in the ordinary displacement of the escapement-rack 70 27 by the dog or rod 35 during operation of the

digit-keys 15, the rear end of the finger 120 does not fall in front of said flange 124.

In the down stroke of any multiple-zero key 84, the accompanying rearward thrust of the corresponding zero-stop-setting bar 95 rotates the escapement-disabling lever 118 to draw the escapement-disabling finger 120 forwardly, so that its rear end falls by gravity in front of the flange 124 of the escapement-rack 27. Said rearward thrust of the bar 95, it will be remembered, is also effective to set the appropriate number of zero-stops 24° and an appropriate carriage-arresting stop 114. Upon return of the depressed zero-key 84 and the accompanying recession of its stop-setting thrust bar 95, the spring 123, acting on the escapement-disabling lever 118, will cause the latter to return to its normal position and thereby thrust the escapement-disabling finger 120 rearwardly, whereby the dropped rear end of said finger 120 will push the escapement-rack 27 rearwardly by acting against the flange 124, as indicated in Figure 2, to release the carriage-structure, including the frame 25 and carriage-slide 46, which thereupon, under the influence of the spring 30, will move to the right, as indicated in Figure 2, until arrested by the rearwardly-projected carriage-stop 114.

Following the operation of a multiple-zero key 84 and the resultant setting of corresponding zero-stops 24° and advance of the carriage-structure 30 25, 46, the machine may be cycled manually by the usual operating handle (not shown), or it may be cycled by power by pressing the cycling key 57.

It may be noted at this point that the Sundstrand machine has the usual plate 125, Figure 4, 35 for opposing, during the cycle, the rise of those denominational bars 38 whose extension rods 48 have not, according to the number of places in the amount indexed, been brought, by the advance of the carriage-structure, into the zone of the nest 40 or field of digit-stops 24.

Since a zero-key 84 is the last key operated in the indexing of an amount ending in one or more zeros, the machine may be cycled automatically in immediate sequence to the advance of the carriage-structure 25, 46, resulting from the operation of said zero-key and the concomitant setting of one or more zero-stops 24°. For this purpose, the following mechanism may be provided.

The transversely extending control bar 127, 50 overlying the carriage-stops 114, is guided for transverse movement, preferably parallel to the movement of the carriage-slide 46 of the carriage-structure in side-members 131, 132 of the digit-stop frame 31, and may have projections, 55 such as screws 134, coacting with the side-member 131, to determine two positions of said control bar 127, one position being the normal or Figure 4 position, in which the control bar is yieldably maintained by a spring 135.

Upon the rearward projection of a carriage-stop 114 and the release of the carriage-structure 25, 46, resulting from operation of a zero-key 24°, the control bar 127 will be displaced rightwardly to the Figure 8 position, as a result of the contact of the released carriage-structure with the projected carriage stop 114. Near the end of its movement to the right, the carriage abutment 116 strikes the projected stop 114 and drives the same, together with the control bar 127 and rack 129, 70 rightwardly until the left hand screw or stop 134 infringes with the side-member 131 to arrest the carriage and the control bar.

The control bar 127, by reason of its rightward displacement, may serve as part of a cycle-trip- 75

ping train arranged to act upon the part or link 59, Figure 5, of the Sundstrand cycle-tripping mechanism. Since, a set carriage-stop 114, is itself displaced rightwardly with the bar 127 before the carriage is finally arrested, the parts are so arranged that the distance which the set stop 114 is from the lug 116, is less than the necessary full extent of carriage-advance, by the amount of the rightward displacement of the stop 114.

10 Said Sundstrand link 59 may have a shoulder or collar 137 against which an arm 138 of an intermediate lever 139 may bear for displacing said link 59 endwise to trip the Sundstrand cycling mechanism when said intermediate lever 139 is operated. A spring 140 operable upon the intermediate lever 139 tends to rock the lever to displace said link 59, but the intermediate lever is normally restrained by a latch 141 pivoted to the lever at 142 and normally caught over a fixed stop 143, Figure 4. Said spring 140 may pull upon said stop-rod 141 in order to act upon the intermediate lever 139. At the left end of the control bar 127, there is pivoted a spring-pressed latch-releasing hook 145 having a stop-ear 146 abutting 20 the edge of the control bar 127 to determine the normal position in which the latch-releasing hook is yieldably maintained by a spring 147. The latch-releasing hook 145 is arranged relatively to the forward end of the latch 141, as shown in 25 Figure 4, so that rightward displacement of the control bar 127 will disengage the latch 141 from the stop 143, whereupon, as indicated in Figure 8, the spring 140 will operate to rotate the intermediate lever 139 to shift the trip-link 59 forwardly, as indicated by the arrow in Figure 8. By reason of the resulting release of the Sundstrand clutch-dog 64 and the closing of the motor-contacts 71, a machine-cycle will then commence, the spring 140, operating through the intermediate lever 139, to maintain the trip link in its operated position. In order that the cycle may not be 30 repeated, it is necessary to permit the trip-link 59 to restore under the pull of its spring 149, inferior to the spring 140, after the forward displacement 35 of the link has effected the release of the clutch-dog 64 and the closing of the contacts 71, it being understood that the restoration of said link 59 permits the pin 63 to return into position to terminate the cycle as hereinbefore described.

40 Therefore, after the clutch-dog 64 has passed the pin 63, the latter may be permitted to return to its normal position by retracting the intermediate lever 139, and, to this end, the driving arm 72 of the cycling rock-shaft 56 may be utilized at 45 the end of its forward stroke to restore the intermediate lever 139 by engaging an arm 144 of the latter, as indicated in Figure 6. Said intermediate lever 139 may swing about a stud 148 mounted on a bearing 149^a for the rock-shaft 56.

When the lever 139 is restored by the driving arm 72, its latch 141 catches over the stop 143 again, as seen in Figure 6; and therefore, when said driving arm 72 in its return stroke, recedes from the arm 144 of said intermediate lever 139, the latter will be held latched to prevent it from initiating another machine-cycle.

50 It is because the carriage-structure 25, 46 is not restored until the end of the cycle, as will presently be more fully explained, that the latch-releasing hook 145 on the control bar 127 for disengaging the latch 141 from its stop 143 is provided, said hook being so arranged relatively to said latch 141 as to permit the intermediate lever 139 to be restored by the driving arm 72 before the carriage-structure and said hook 145 are moved

leftward for restoration. This arrangement is as follows: Obviously, as the latch-releasing hook 145 travels with the control bar 127 on movement of the latter to the right, the hook draws with it the latch 141, which rocks counter-clockwise on its pivot 142 relatively to the intermediate lever 139, until the latch disengages from its stop 143, whereupon the superior spring 140 rocks the intermediate lever 139 counter-clockwise to cause it to trip the motor clutch and complete the motor circuit, as described.

5 Said Sundstrand link 59 may have a shoulder or collar 137 against which an arm 138 of an intermediate lever 139 may bear for displacing said link 59 endwise to trip the Sundstrand cycling mechanism when said intermediate lever 139 is operated. A spring 140 operable upon the intermediate lever 139 tends to rock the lever to displace said link 59, but the intermediate lever is normally restrained by a latch 141 pivoted to the lever at 142 and normally caught over a fixed stop 143, Figure 4. Said spring 140 may pull upon said stop-rod 141 in order to act upon the intermediate lever 139. At the left end of the control bar 127, there is pivoted a spring-pressed latch-releasing hook 145 having a stop-ear 146 abutting 20 the edge of the control bar 127 to determine the normal position in which the latch-releasing hook is yieldably maintained by a spring 147. The latch-releasing hook 145 is arranged relatively to the forward end of the latch 141, as shown in 25 Figure 4, so that rightward displacement of the control bar 127 will disengage the latch 141 from the stop 143, whereupon, as indicated in Figure 8, the spring 140 will operate to rotate the intermediate lever 139 to shift the trip-link 59 forwardly, as indicated by the arrow in Figure 8. By reason of the resulting release of the Sundstrand clutch-dog 64 and the closing of the motor-contacts 71, a machine-cycle will then commence, the spring 140, operating through the intermediate lever 139, to maintain the trip link in its operated position. In order that the cycle may not be repeated, it is necessary to permit the trip-link 59 to restore under the pull of its spring 149, inferior to the spring 140, after the forward displacement 30 of the link has effected the release of the clutch-dog 64 and the closing of the contacts 71, it being understood that the restoration of said link 59 permits the pin 63 to return into position to terminate the cycle as hereinbefore described.

35 As the shoulder of the latch 141 clears its stop 143, the spring 140 snaps the shoulder of the latch over the stop, thereby causing the latch 141 to shift farther towards the free end of the releasing hook 145.

40 Such restoration of the intermediate lever 139 and its latch occurs at about the completion of a half cycle, while the control bar 127 remains in its right-hand position to which it was shifted 35 due to the impact of the carriage slide 46, 116 against the set carriage stop 114.

45 As the driving arm 72 rocks the intermediate lever 139 and withdraws its forked end 138 from the collar 137, the inferior spring 149 restores the 40 tripping link 59 to its normal position, to enable the disconnection of the clutch and the interruption of the motor drive. Discontinuance of the motor drive at this point enables the usual adding machine return spring, tensioned during the 45 forward stroke, to restore the parts to their normal positions. Furthermore, the provision of the yielding, latch-releasing hook 145 also permits the intermediate lever 139 to be restored for preventing repetition of the cycle when the repeat-key 81 is set, it being remembered that the setting of said repeat-key 81 prevents the restoration of the carriage-structure 25, 46 during a 50 cycle.

55 In the ordinary operation of the machine, that is, when the repeat-key 81 has not been set, the carriage-structure 25, 46 is restored by means of the push-rod 77 at the end of the cycle, as hereinbefore explained.

60 As heretofore explained, the carriage-slide 46 with its vertical rods 48, and the traveling frame 25 with its post 22 and thrust-rod 20, are restored to their normal left-hand positions during the last half cycle of operation of the machine, through the thrust imparted by the restoring link 65 77, (Fig. 4), to the projecting stud 78 and its restoring slide 79 connected with the traveling frame 25.

65 The restoring link 77 imparts sufficient thrust to the carriage-slide, traveling frame and post 22 to 70 overthrow the parts past their normal positions, the forward end of the link 77 then disengaging itself from the roller stud 78 and dropping out of its path of movement rearwardly, so that the escapement feed spring 30 may restore the parts 75

to the right until the corner edge of the post 22 is arrested by the face of the first tooth 27^a (Fig. 10).

The withdrawal of the carriage-slide 46 from contact with the projected carriage-stop 114 against which it has been pressed by the strong spring 30 and frame 25, enables the weaker spring 135 to restore the control bar 127, supporting plate 129 and row of carriage-stops 114 to their normal positions determined by the right-hand stop 134.

The control bar 127, on such return, projects its latch-releasing hook 145 past the farther edge of the bar 159 of the previously restored latch 141, whereupon the spring 147 snaps the bill of the releasing hook over the ear preparatory to a subsequent operation of the parts. There is thus provided an excess of leftward carriage-restoring movement represented by the space 160, Figure 10, separating the post 22 from the first escapement-tooth 27^a. This excess carriage-structure movement may be utilized for the purpose of the invention as follows.

The rack-displacing finger 120, which, it will be remembered, was caused to drop in front of the flange 124 of the escapement-rack 27 upon depression of any of the zero keys 84 and to then displace the escapement rack upon release of the depressed zero key, to release the carriage-structure, will, by said excess restoration of the carriage-structure, escape the left end of said flange 124, thereby permitting the escapement-rack 27, under the pull of its spring 29, to restore to operative position, as in Figure 10. Upon the advance of the carriage-structure, from its overthrown position to its normal starting position, under the pull of its spring 30, the rear end of the rack-displacing finger 120 will ride up an incline 124^a at the left end of the flange 124, and come to rest on the top edge of said flange, as in Figure 7.

The excess restoring movement of the carriage-structure 25, 46 during a cycle may also be employed to restore whichever carriage-stop 114 was set rearwardly. To this end, a carriage stop-restoring plate 151, (Figs. 3, 4, and 9), is mounted facewise against the bottom of the grooved plate 129, in which the carriage-stops 114 play, so that a front edge of said plate 151 opposes the rear faces 50 of the downwardly-projecting tongues 152 of the several carriage-stops 114. Said plate 151 is normally in position wherein its said front edge is spaced rearwardly from the rear faces of said tongues 152, as indicated in Figure 4, whereby the stops 114 are projectable rearwardly without hindrance from said restoring plate 151.

As indicated in Figure 3, the stop-restoring plate 151 has a rearwardly-extending tab 154, an abrupt edge of which lies in the return path 60 of the lug 116 of the carriage-slide 46 of the carriage-structure, so that, during the excess restoring movement of the latter, the restoring plate 151 will be displaced endwise relatively to the row of carriage-stops 114, assuming that the latter 65 have been restored to their normal left-hand positions by the spring 135 on the control bar 127. This endwise displacement of the stop-restoring plate 151 is also utilized to cause forward displacement of said plate 151 by means of inclined 70 cam-slots 154^a, through which pass camming studs 156 depending from the bottom of the stop-rack 129, said camming studs 156 also serving to retain the plate 151 adjacent the bottom of said rack. Thus the excess restoring movement of 75 the carriage-structure causes forward edgewise

displacement of the plate 151, as indicated in Figure 9, and thereby, any carriage-stop 114 that was set rearwardly will be restored. Upon the advance of the carriage-structure from its overthrown position to the first escapement-tooth 27^a, 5 a spring 157 restores the plate 151 to its normal Figure 4 position relatively to the control bar 127 and the row of carriage-stops 114.

The tab 154 of the plate 151 may also be utilized during the excess carriage-restoring movement to 10 insure the leftward restoration of the control bar 127 and the row of stops 114, and for this purpose the left side of said tab 154 may abut a downwardly-bent ear 158 of the control bar 127, said ear also serving to attach the spring 135. 15

As shown in Figure 4, the edges 95^a of the zero-stop-setting thrust bars 95 are normally spaced somewhat forwardly of the faces 107 of the zero-stops 24^a, and similarly, the tongues 113 of said bars 95 are normally spaced somewhat forwardly 20 of the shoulders 115 of the carriage-stops 114. It will also be seen in Figure 1 that the rear end of the escapement-rack-displacing finger 120 normally lies somewhat forwardly of the front of the flange 124 of said rack at the beginning of the 25 return, rack-displacing stroke of the operated zero-key 84. It follows, therefore, that, by the time the escapement-rack 27 has been displaced far enough for releasing the carriage-structure, the zero-stop-setting thrust bars 95 and their tongues 113 will have restored sufficiently to clear, respectively, the zero-stops 24^a and the carriage-stop shoulders 115, so as not to impede the movement of the released carriage-structure.

The operation of the invention will be understood from the foregoing description of details of the illustrated and preferred embodiment of the invention, and the operation may also be summarized as follows:

It is assumed that all the parts of the machine 40 have been brought to their normal positions, Figures 4, 5 and 7, preparatory to indexing an amount, such as 750000, for example. The "7" and "5" digit-keys 15 are successively operated to index the first two significant digits of said amount. It 45 will be understood that, according to the usual operation of a ten-key machine, the first two digits 7 and 5 will be indexed, respectively in the first and second columns from the left of the nest or field of digit-stops 24, and, accordingly, at 50 each operation of a digit-key 15, the carriage-structure 25, 46 will advance a single step under control of the escapement-rack 27, so that when the 5 digit-key is operated, the extension rod 48 of the denomination bar of lowest order will register with and lie beneath the second column from the left of the nest or field of digit-stops, as seen in Figure 1.

When the "5" digit-key has been operated the step by step advance of the carriage will have 60 positioned the set of zero-stop-setting thrust bars 95 with the left end portions of their zero-stop-setting edges 95^a opposite the third column of digit-stops 24, the column of stop-setting rods 20 also then pointing to said third column of stops. 65

Since said amount "750000" has a succession of four final zeros, the "0000" key 84 is now operated to index at one key-stroke said final zeros. The corresponding zero-stop-setting thrust bar 95 is thereby projected rearwardly during the 70 down stroke of said "0000" key 84, as shown in Figure 1, and is operative according to the length of its edge 95^a, to simultaneously set a zero-stop 24^a in the third, fourth, fifth and sixth columns of the nest or field of stops. Also during the 75

down stroke of said key 84 the sixth carriage-stop 114 from the left end of the row of such stops is set rearwardly by the tongue 113 of the rearwardly-projected thrust bar 95. At the end of said down stroke of the operated key 84, the thrust-finger 120 will have been moved forwardly by the universal lever 118 driven by the rearwardly-projected thrust bar 95, and the rear end of said finger 120 will have been drawn off the flange 124 10 and have fallen in front of the flange of the escapement-rack 27, as shown in Figure 1.

Upon release of the depressed multiple-zero key 84, the spring 92, acting through the bellcrank lever 90, returns the key to its normal position 15 and also retracts the rearwardly-projected zero-stop-setting thrust bar 95, and at the same time, the spring 123, acting through the escapement-disabling lever 118, moves the thrust-finger 120 rearwardly, to displace the escapement-rack 27 20 for releasing the carriage-structure 25, 46 to the action of the spring 30. By the time the escapement-rack 27 has been displaced far enough to release the carriage-structure, the zero-stop-setting thrust bar 95 will have moved sufficiently 25 forwardly in its retractive movement, to clear the zero-stops 24° and the row of carriage-stops 114.

As soon as the carriage-structure becomes released, it advances rightwardly under the pull of its spring 30 until it contacts with the rearwardly-projected carriage-stop 114. The released carriage-structure in striking the rearwardly-projected stop 114 moves the latter, together with the control bar 127 on which the stops 114 are mounted, rightwardly until the left hand stop 134 35 of the control bar 127 strikes the side-member 131 to arrest the rightward advance of the carriage-structure, as indicated in Figure 8.

The tongues 113 of the several zero-stop-setting thrust bars 95 lie respectively at such distances from the lug 116 on the carriage-structure, with which said bars 95 advance in the ordinary step-by-step feeding advance of the carriage, that operation of a multiple-zero key 84 at any position of the carriage-structure sets a stop 114 40 sufficiently spaced from said lug 116 to predetermine an extent of carriage-advance according to the number of zeros represented by the operated zero-key 84. Thus, the "0000" key operated for the four final zeros of said amount "750000" 45 will set that stop 114 which is the fourth one to the right of the lug 116, as indicated in Figure 1, to thereby predetermine a carriage-advance equivalent to four ordinary steps. The advance of the carriage-structure effected by the operation of the "0000" key for indexing said amount "750000" will bring the first six columns of nest or field of stops 24, 24 into register with the six 50 denominational bars 38 at the right.

As indicated in Figure 8, the rightward displacement of the control bar 127 will have disengaged the latch 141 from its stop 143 to thereby permit the intermediate lever 139, under the pull of the spring 140, to shift the Sundstrand cycle-tripping link 59 forwardly for initiating a machine-cycle. During said machine-cycle, the last six denomination-bars 38 will rise to different positions in accordance with the indexed amount, the other bars being held down by means of the stop-plate 125, since said other bars 55 have not, during the advance of the carriage-structure, passed from under said stop-plate 125.

About the end of the first half of the cycle, the intermediate lever 139 will have been restored by the arm 72, to thereby release the clutch-pin 63 for terminating the cycle. During 60

the last half of the cycle, the raised denomination-members 38 are restored by the usual restoring bail (not shown) of the Sundstrand machine. The carriage-structure is also restored during the last half of the cycle by the push-rod 5 77 which advances the restoring link 79. During the return movement of the carriage-structure, the post 52 of said structure passes over all the rearwardly-projected stops 24 including the zero-stops 24° and cams all the stops that were 10 set forwardly to their normal positions. Near the end of the cycle, the carriage-structure 25, 46 reaches the end of its restoring movement, which, as indicated in Figures 9 and 10, due to the excess movement imparted, retracts it to a 15 point somewhat past the normal position determined by the first escapement-tooth 27a. During the excess movement, the carriage stop-restoring plate 151 becomes operative to return the rearwardly-projected carriage-stop 114. The 20 escapement-rack 27 is also restored to operative position during said excess movement, as shown in Figure 10. The restoring movement of the carriage-structure is terminated by the disconnection of the push-rod 77 from the stud 78 of the 25 carriage-restoring link 79, whereupon the carriage advances under the pull of its spring 30 until arrested by the first escapement-tooth 27a. In this advance movement, the carriage stop-restoring plate 151 reassumes its normal position 30 under the pull of its spring 157; and the thrust finger 120 reassumes its normal position upon the top of the escapement-rack flange 124. The cycle of operations is now completed and the machine is ready for indexing and registering 35 another amount, it being noted that the return of the carriage-structure has permitted the spring 135 to return the control bar 127 and stops 114 rightwardly and bring the releasing hook 145 of said bar 127 back into cycle-tripping position. 40

It will be seen now that for indexing and listing the illustrative amount "750000", only three key-operations were necessary, according to the invention, whereas, heretofore, seven key-operations were required, namely, one operation of a digit-key 15 for each of the six digit places of the amount, and then the operation of the usual cycling key 57. 45

As indicated in Figures 1 and 4, the keyboard plate 87 may rest on spaced upright plates 162. The right-hand one of said plates 162 may carry studs 163 for supporting the angle-bar 88, in which the lower ends of the multiple-zero key-stems 85 are guided, it being noted that said angle-bar 88 also has pivot-studs 164 (Figs. 1 and 7), for the bell crank levers 90 of the trains operated by the multiple-zero key-stems 85. Said plates 162 may rise from the plate 99, which rests upon a base 165 of the machine. The machine has the usual casing 166 (Fig. 4) which also frames the keyboard-plate 87, formed as indicated to include the file of zero-keys 84. 55

Variations may be restored to within the scope of the invention, and portions of the improvements may be used without others. 60

Having thus described my invention, I claim:

1. In a ten-key adding machine, the combination of a key-operated mechanism for indexing an amount digit by digit, mechanism which may 70 be tripped for cycling the machine subsequently to the indexing, a plurality of special keys selectively operable for indexing one or more final zeros of an amount at one key-stroke, and means called into play by operation of any one of said 75

special zero-keys to automatically trip said last-mentioned mechanism to cycle the machine.

2. The combination of columns of digit-stops for a set of reciprocatory denomination-members, each column including a zero-stop, key-operated means including a step-by-step feeding carriage for indexing said stops, including the zero-stops, column by column, a plurality of multiple-zero keys representing different pluralities of successive zeros in an amount, and a member connected to each multiple-zero key and operable by the latter at a single stroke to simultaneously set in adjacent columns a plurality of zero-stops corresponding to the plurality of zeros represented by said key, said members being arranged to collectively move with said carriage, whereby, in any position of the latter for indexing a column of stops, the operation of a multiple-zero key at said column sets the zero-stop in said column and also sets a zero-stop in one or more succeeding columns depending on the plurality of zeros represented by the operated key.

3. In a machine of the class described, the combination with a power-drive tripable for cycling the machine, and digit-keys and a carriage co-operative with said keys for indexing an amount digit by digit preparatory to the cycling, said carriage advancing a step after each key-operation, of a special key operable for stepping the carriage at a final zero of an amount, and means conditioned by operation of said special key to co-operate with said carriage and thereby enable the latter in its ensuing step to trip said power-drive to cycle the machine.

4. In a machine of the class described, the combination with digit-keys, a co-operating step-by-step feeding carriage for indexing an amount digit by digit, and a power-drive tripable to cycle the machine after the indexing, said carriage advancing to different final positions dependent upon the number of digits in the amount indexed, of a special key operative for effecting the final carriage-step, and means actuated by said carriage as an incident to a final step of movement under the influence of said special key to trip said power-drive irrespective of the position assumed by said carriage at the conclusion of said final step.

5. The combination of digit-keys, a spring-driven carriage, an escapement-member normally restraining the carriage and operable by said keys to enable the carriage to advance step by step from a starting position for indexing an amount, a special key, a carriage-stop settable to effective position by operation of the special key, and means whereby said special key operation casts off the escapement-member to a detented position for a final jump of the carriage to the set carriage-stop, said means being arranged so that the return of the carriage to starting position restores the cast-off escapement-member to effective position.

6. The combination of amount-indexing digit-keys, a spring-driven carriage, an escapement-rack, a dog normally engaging a rack-tooth for restraining the carriage, an element operable by any digit-key to co-operate with the rack and dog for effecting a step-by-step feed of the carriage, a special key, a carriage-stop settable to effective position by the down stroke of said special key, and a member brought from ineffective to effective position by the down stroke of the special key, so as to disengage said rack and dog by the return stroke of the special key, whereby the car-

riage makes a final jump to the set carriage-stop, said dog and rack being kept disengaged by said member after the return stroke of said special key, said member being arranged to become restored to its ineffective position by the return of the carriage to starting position, whereby said rack and dog become re-engaged.

7. In a machine of the class described, the combination of an amount-indexing means including a carriage advancing to different final positions depending upon the number of digits in the indexed amount, a power-drive for cycling the machine, a member displaceable to trip said power-drive, a special key operable for jumping the carriage to a final position, and a train whereby the carriage at the end of the jump effected by said special key displaces said member to trip the power-drive for a cycle, the return of the carriage being timed to occur during the concluding part of the cycle, said train being arranged to permit restoration of the displaced tripping member during the cycle before the carriage is returned, whereby repetition of the cycle is prevented.

8. In a machine of the class described, the combination of an amount-indexing means including a carriage advancing to different final positions depending upon the number of digits in the indexed amount, a power-drive for cycling the machine, a member displaceable to trip said power-drive, a special key operable for jumping the carriage to a final position, a train whereby the carriage at the end of the jump effected by said special key displaces said member to trip the power-drive for a cycle, during which the carriage is ordinarily returned, and a repeat-key mechanism settable to prevent return of the carriage during a cycle, said train being arranged to permit restoration of the displaced tripping member during the cycle independently of the return of the carriage, whereby repetition of the cycle is prevented when the repeat-key is set.

9. In a machine of the class described, the combination of a set of denomination-members, columns of settable digit-stops therefor, including zero-stops, a power-drive tripable for cycling the denomination-members, a single set of digit-key-operated stop-setters, a carriage co-operating with said stop-setters, to enable the latter to set the digit-stops column by column and to effect a relative shift of the denomination-members and digit-stop columns, a plurality of key-operated special stop-setters selectively operable and arranged relatively to the zero-stops for simultaneously setting one or more zero-stops, that is, one zero-stop in the column corresponding to the carriage-position and, additionally, one or more zero-stops in succeeding columns, means whereby the carriage is ensuingly caused to be advanced in correspondence with the number of columns in which a zero-stop is set by operation of a special stop-setter, and means whereby the power-drive is automatically caused to be tripped when the carriage has been advanced by operation of a special stop-setter.

10. In a machine of the class described, the combination with a keyboard; a field of stops; a carriage traversing the field of stops; and an escapement to normally restrict the carriage to a step-by-step advance; of a key-actuated member to simultaneously set a plurality of stops of the field of stops; a group of individual carriage stops normally out of the path of advance of the traveling carriage, and past which the carriage and the key-actuated member normally move,

an appropriate one of which carriage stops is set into the path of the carriage by the key-actuated member; and an escapement-tripping mechanism operable by the key-actuated member to free the carriage for uncontrolled advance to contact the set carriage stops.

11. The combination with numeral keys; spring-driven carriage; a field of stops past which the carriage travels; and an escapement-member normally restraining the carriage, and operable by the keys to enable the carriage to advance step by step; of a special key adapted to set a stop to effective position; a normal idle disabling device for the escapement member, and controlled by the special key to disable the escapement member and retain it in such position; and means to restore the carriage to its home position, and to enable the escapement-disabling device to return to its idle position.

20 12. A zero indexing mechanism for motor driven machines of the class described, including a motor and clutch; trip mechanism to condition the motor clutch for operation; a traveling carriage; an escapement, including a carriage feed means and a rack to advance the carriage step-by-step; normally idle means to disconnect the rack and traveling carriage to free the carriage from the control of the escapement; stops to variously arrest the carriage when freed from its escapement; indexing stops; and a key to set an indexing stop, and an appropriate carriage stop, and condition the means for disconnecting the rack and carriage; to enable the carriage to actuate the motor-clutch tripping mechanism.

35 13. In a motor-driven machine of the class described, the combination with a clutch normally disconnecting the motor and the machine; a field of indexing stops; key-controlled means to project selected stops; a traveling carriage; an escapement mechanism including a rack and detent to advance the carriage step by step; and means to restore the carriage; a group of carriage stops; key-controlled means for operating said stops; an escapement-disabling means also rendered effective by said last key-controlled means; means automatically operable to trip the clutch control to render the clutch effective to connect the motor and the machine; a latch to hold the automatically operable clutch-tripping means ineffective, a shiftable support for the group of carriage stops and having a limited movement; means releasably connecting the shiftable support and the latch to enable impact of the carriage against a carriage stop to move the shiftable support to release the latch and free the clutch-tripping means for operation; and means to restore the clutch-tripping means

to latched position irrespective of the position of the shiftable support.

14. In a motor-driven calculating machine, the combination with a clutch to connect the motor and the machine, clutch-control means normally tending to hold the clutch ineffective; keys; a field of key-set indexing stops; a traveling carriage; an escapement therefor; and means controlled by a key to disable the escapement; of a group of key-controlled carriage stops shiftable transversely of the path of the carriage to arrest the latter when the escapement is disabled, and also shiftable in line with the path of the carriage; a second clutch control means superior to the first-named clutch control means, to overcome such first-named means and render the clutch effective; latching means under control of the projected carriage stop to retain the superior clutch control means ineffective; the carriage by its impact against the projected carriage stop effective to shift the carriage stop bodily in the plane of travel of the carriage to disable the latching means and release the superior clutch-control means to enable it to engage the clutch for operation; and motor-driven means to restore the superior clutch control means to latched position irrespective of the position of the carriage stop-controlled latch-disabling means, to enable the operation of the first-named clutch control.

15. In a motor-driven calculating machine, the combination with a clutch to connect the motor and the machine, clutch-control means normally tending to hold the clutch ineffective; keys; a field of key-set indexing stops; a traveling carriage; an escapement therefor; and means controlled by a key to disable the escapement; of a group of key-controlled carriage stops shiftable transversely of the path of the carriage to arrest the latter when the escapement is disabled, and also shiftable in line with the path of the carriage; a second clutch control means superior to the first-named clutch control means, to overcome such first-named means and render the clutch effective; latching means under control of the projected carriage stop to retain the superior clutch control means ineffective; the carriage by its impact against the projected carriage stop effective to shift the carriage stop bodily in the plane of travel of the carriage to disable the latching means and release the superior clutch-control means to enable it to free the clutch for operation; means to return the carriage; and means effective upon the return of the carriage to re-establish the control of the carriage stops over the latching means.

LAWRENCE E. LENTZ.
